ABSTRACT: A system for indicating to a plurality of administrative stations, by signal means, the status of the individual unit. Preferably, the administrative station adjacent the unit has means controlling the signals to energize the signaling means in all stations simultaneously to indicate the status of the unit. For example, in a hospital the system would indicate the status of a patient-bed unit. It would be controlled at the nurses' station to supply the proper signals to energize the signal means and alert the cashier, admitting office, housekeeper, dietician and other desired administrative stations that the bed is occupied, the patient is to be discharged, the patient has left the bed and it should be made up, and that the bed is ready for occupancy so that each administrative station can be ready to perform its required function.

Heretofore in a hospital, for example, the records for each patient-bed unit were filed in filing cabinets at each administrative station and the status of each unit was not readily discernible. When there was any change in the unit status, it was necessary for the nurse or someone to advise each station individually. The record was then removed from the file and acted upon accordingly. 21

SYSTEM FOR SIMULTANEOUSLY INDICATING A UNIT STATUS AT A PLURALITY OF STATIONS

The present invention greatly simplifies the prior practice by providing a system for each bed unit including a series-connected signal means in all of the required administrative stations so that applying a signal to the system will simultaneously and instantaneously energize all of the signal means to provide readily recognized signals indicative of the unit status. The system is usually controlled at a nurses' station adjacent the bed unit so that the bed status can be quickly and accurately determined and the proper signal impressed on the system to operate all of the signal means in such a manner as to alert and advise the various administrative stations, such as cashier, admittance, housekeeper, dietician or the like, of the bed status.

Preferably, the signal means are electric lights which give an easily visible indication. They are connected in series and, when the system is energized in a predetermined manner, simultaneously impart the desired information to all stations. In some situations means can be provided at the stations for changing the character of the signal means, for example, the color of the lights, to provide additional information.

As a safety measure, a high resistance shunt can be provided for each light to maintain the continuity of the system should the light burn out and, additionally, to indicate that there is a burned out light by reducing the intensity of the other lights.

The system of the present invention, while highly advantageous for patient-bed status for hospital use, can also be effective in nursing homes, hotels, motels, factories and in any other situation wherein it is desired to give the status of a unit simultaneously to a plurality of administrative stations by impressing on the system a predetermined signal and actuating the series-connected signal means in all stations.

Other features and advantages of the invention will be apparent from the specification and claims when considered in connection with the accompanying drawings in which:

FIG. 1 is a schematic diagram of a status system for a patient-bed unit.

FIG. 2 is a view, partly in section, of a switch means.

The present invention is herein illustrated as being used in a hospital to alert various administrative stations as to the status of the patient-bed units in the hospital.

In carrying out this invention, a system is provided for each patient-bed unit. Since all are essentially the same, only one is illustrated herein.

As shown in the drawings, the system includes a plurality of administrative stations, such as a nurses' desk or station 10, a cashier's station 11, a patient admitting station 12, a housekeeper's station 13 and a dietician's station 14, each of which has a signal means 10a, 11a, 12a, 13a and 14a.

While various types of devices capable of attracting attention and giving a signal may be employed, the signal means, as herein illustrated, are preferably electric lights 15 which are connected in series by a single conductor 16 connected to a low voltage D.C. source of energy 17 sufficient to operate the signal means simultaneously, when a predetermined signal is impressed on the system, to indicate, if desired, one of four statuses of the patient-bed unit. For example, if the lights are off, it indicates that a patient occupies the bed; if the lights are slowly flashing, it indicates that the patient is scheduled to leave the hospital; if the lights are rapidly flashing, it indicates that the patient has left the bed; and if the lights are on steady, it is an indication that the bed is made and is ready for occupancy. If additional information is to be provided by the system, it may have other signals impressed on it to energize the signal means at the stations to function in a distinctive manner to indicate this additional status information, for example, the lights could be energized to flash with a different frequency or sequence.

It is preferred to control the operation of the system from the nurses' station 10, which is usually close to the patient-bed unit so that the status thereof can be quickly and accurately determined and the proper signal impressed on the system to

operate all the signal means to alert the various administrative stations of the unit status. This is accomplished by switch means 18 at the nurses' station comprising a single-pole, double-throw switch 19 and a double-pole, double-throw gang switch 20. If the two switches are in the position as shown in the drawing, this will connect the series circuit for the signal means to ground through a slow flasher 21. This will automatically provide the necessary signal for causing the lights 15 in each of the signal means at the various administrative stations to flash slowly. The light at the nurses' station will be visually checked by the nurse to insure that the proper signal is being given. The slowly flashing light at the cashier's station will alert the cashier that the patient will be needing the bill; at the admitting office the signal alerts the admitting clerk that the bed will be vacant so they can schedule another patient; at the housekeeping station it reports that a bed will be ready to be cleaned and a work ticket can be issued; and the light at the dietary station alerts the dietician that the unit will not need a meal.

When the gang switch 20 is moved to the right as viewed in the drawing, it will connect the circuit to ground through the fast flasher 22. This will alert the cashier that the patient is on his way to pay the bill; it will also advise the admitting office that the bed will soon be ready; it alerts the housekeeper that the bed is ready for cleaning and should be taken care of promptly.

When the switch 19 is thrown to the left, it will connect the system to ground through the "on" contact and the light 15 in all of the stations will remain a steady "on". This switching is done at the nurses' station after the bed has been made up and so advises the housekeeping station and alerts the admitting office that the room is ready for the admission of a new patient. If the gang switch 20 is moved to the left, the circuit will be connected to the "off" contact which will extinguish all of the lights. This is accomplished at the nurses' station when the patient has been assigned to the room and the bed is occupied. The switch will stay in this position until a new cycle of operations is required.

It will be noted in the drawings that the signal means at the nurses' station has a second light 30 which is connected to a second light 31 at the cashier's station by a conductor 32. These lights 30, 31 are in a second circuit which may be substituted for the lights 15 in the two stations. These lights are the same but are of a different character, for example, a different color, from lights 15. A switch 33 at the cashier's station will permit the cashier to substitute these two lights 30, 31 for lights 15 in each station after the patient has made a proper settlement with the cashier so as to indicate to the nurses' station, as well as to the cashier's station that the financial arrangements with respect to this unit have been taken care of. Thus, the character of the signal means at the nurses' station and cashier's station is altered by the action of the switch 33 and provides additional information at said stations.

Also, at the admitting station the signal means includes a second light 34 of different character from light 15, preferably of a different color, and a switch 35 is so connected as to selectively connect either light into the system to change the character of the signal means and to provide additional information at the admitting station. For example, lights 15 and 34 can be pink and blue respectively to designate the sex of the unit so that a man will not be assigned to a ladies' ward or vice versa.

In each of the above situations, while the character of the signal means is changed, the energization of the system is not altered so that the signal means will continue to give one of the four signals impressed on the system, as controlled at the nurses' station, to show the status of the patient-bed unit.

In some stations it may be desirable to provide additional information; for example, in the cashier's station it may be advisable to indicate that the bill has been prepared in response to a slow flashing light and is awaiting the patient, or in the admitting office an indication may be given that the bed needs repair and that the particular unit should not be assigned. This

can be readily accomplished by providing the actuator of the switch means with a readily changeable colored button. One such arrangement is shown in FIG. 2 wherein the actuator 35a of the switch 35 has a removable cap 36 of plastic of a predetermined color to provide additional status information.

As a safety measure it will be noted that each of the lights is provided with a normally ineffective bypass which becomes operative in the event the light burns out. While this may take many forms, in the illustrated form of the invention a high resistance 40 is provided in shunt relation with each light so that in the event one of the light burns out, the circuit will not open but will be transferred through the shunt. This being a high resistance shunt will cause the lights to be dimmed and alert the administrative stations to the fact that a light is burned out and it can be checked by following the circuit through the various administrative stations.

Should it be desired to include other administrative stations in the system, it is merely necessary to connect a similar signal means at such station in series with the other stations of the system and adjust the voltage source to operate the added signal means as required.

With the present system it will be clear that visual signals are given in each of the administrative stations to indicate the status of the patient-bed unit and to alert each of the administrative stations as to the activity that is required with respect to the unit. These signals function instantaneously and provide a visual means for determining the status in a simple, accurate and expeditious manner.

While the present system has particular use in hospitals, it can, by proper selection of the components of the system, be also used in nursing homes, hotels, motels, factories or in any situation wherein it is desired to simultaneously give to a plurality of stations the status of a particular unit in such a manner that is readily and easily recognized.

Variations and modifications may be made within the scope of the claims and portions of the improvements may be used without others.

I claim:

1. A system for automatically indicating to a plurality of sta-

tions the patient-bed status of an individual bed unit in a hospital, comprising a nurses' station adjacent said unit and a plurality of administrative stations, each station having signaling means, and single conductor means for each unit electrically connecting all of the signaling means in series, said single conductor means having one terminal connected to a source of power, said nurses' station having switching means for connecting the other terminal of the single conductor means to ground for turning on the system and for selectively applying one of a plurality of signals to the system to energize the signaling means in each station to denote the patient-bed status of the unit.

5 2. The invention as defined in claim 1 wherein one of the administrative stations is the cashier's station, and wherein 15 means is provided at said station for altering the character of the signaling means at the nurses' station and cashier's station to indicate the status of the patient's account.

3. The invention as defined in claim 1 wherein one of said 20 administrative stations is the admitting office and wherein means is provided at said station for altering the character of the signaling means at said station to provide additional information with respect to said bed unit.

4. The invention as defined in claim 1 wherein the signaling means comprises electric lights.

25 5. The invention as defined in claim 4 wherein said lights can be selectively energized by switch means at said nurses' station to provide a steady, slow flashing or fast flashing light, and extinguished to provide said plurality of signals.

6. The invention as defined in claim 2 wherein the signaling 30 means at the nurses' station comprises a pair of differently colored lights and wherein the signal means in the cashier's station comprises a pair of similar differently colored lights, and switch means at said cashier's station for selectively energizing similarly colored lights in each station.

35 7. The invention as defined in claim 6 wherein the signaling means at the admitting office comprises differently colored lights and switch means at said station for selecting the color of the light to be energized.

UNITED STATES PATENT OFFICE
CERTIFICATE OF CORRECTION

Patent No. 3,599,199 Dated August 10, 1971

Inventor(s) Earl L. Bunting

It is certified that error appears in the above-identified patent and that said Letters Patent are hereby corrected as shown below:

In column 3, line 11, "light" should read --lights--;

In column 4, line 35 "claim 6" should read --claim 3--.

Signed and sealed this 11th day of January 1972.
